UNITED STATES PATENT OFFICE

GORDON T. WHITAKER, OF BEVERLY, MASSACHUSETTS, ASSIGNOR TO EMPIRE METAL PRODUCTS CO. INC., OF LYNNFIELD, MASSACHUSETTS, A CORPORATION

FLASHING

Application filed July 12, 1928. Serial No. 292,212.

This invention relates to flashings such as are used in the buildings trades over and above window and door casings, and elsewhere in construction work to prevent leakage.

It has for its purposes, to provide a new and novel flashing shaped to allow its projection away from the finished plane during the construction period, to freely permit the unobstructed passing of moulding and finishing stock thereunder, and to automatically hug the material over which it rests when construction is finished; to materially conserve the time, tools, patience and energy of journeymen; to minimize construction cost; to make possible a more uniform, finished and perfected job than has heretofore been possible; to eliminate the tacking of flashings at the visible finished area; to insure a smooth, even, surface throughout the visible area; to provide a perfected contact and "tight hug" of the flashing at its exposed edges; to insure greater wear and longer life, both to the flashing and to the material thereunder; to eliminate the discoloration from rain and moisture; and to provide the various other advantages and results made evident from the following specification.

I accomplish the objects of my invention by a specially formed flashing, substantially as shown in the accompanying drawings in which the angles formed by the three members hereinafter fully referred to are respectively a trifle more and a trifle less than 90°. In use the upper nearly vertical member of the flashing, extending from the horizontal member at an included angle of more than 90° is preferably tacked in the desired position at the upper edge thereof. This allows the lower nearly vertical member, extending from said horizontal member at an included angle of less than 90°, to project away from the finished plane during the period of construction, and at the completion of such period it is automatically pressed and held against the finished plane by the application of the material over and above said horizontal member.

Referring to the accompanying drawings, which form a part of this specification, Fig-

ure 1 shows an end view of my improved flashing. Figure 2 shows the flashing as first applied during the construction period. Figure 3 shows the flashing in finished position at the completion of construction. Figure 4 shows a front view of the flashing in finished construction.

Referring again to Figure 1, A shows the upper nearly vertical member of the flashing extending from the horizontal member at an included angle B of more than 90°, C shows the horizontal member. D shows the lower nearly vertical member extending from the horizontal member at an included angle E of less than 90°. Referring again to Figures 2, 3 and 4, F shows the building stud. G shows the board. H shows the casing. I shows the moulding and J shows the clapboard, siding, or other exterior covering material.

Throughout the detailed description and on the several figures of the drawings, similar parts are referred to by like reference characters.

The moulding I is often placed in position upon the casing H after the flashing A—C—D is secured to the structure and for that reason the extended position of the flashing, as indicated in Figure 2, during the construction period is particularly desirable and advantageous so as to allow a free and unobstructed clearance thereunder. At the completion of construction period, with the clapboard or other material J and the moulding I permanently fixed, the angled construction of the flashing causes it to exert a "tight hug" over and about the top of the casing H and the moulding I as shown in Figure 3. My improved flashing is preferably formed from metal but any desirable or suitable material may be used.

While I have illustrated and described a preferred construction for carrying my invention into effect, this is capable of variation or modification without departing from the spirit of the invention. I therefore do not wish to be limited to the exact details of construction herein set forth but desire to avail myself of such variations and modifications as come within the scope of the appended claims.

It will be understood that the terms, vertical, nearly vertical, and horizontal are not intended to imply that the respective members necessarily are used on vertical, near vertical and horizontal positions, as the flashings are intended for use according to the varying requirements of construction purposes, and the terms referred to are merely for descriptive and reference purposes.

Having thus described my invention I claim as new and desire to secure by Letters Patent of the United States of America:

A flashing for use in building construction, comprising a substantially horizontal body portion adapted to seat upon an outstanding ledge of a building element such as a window frame, an upstanding flange portion along one edge of said body portion and inclined at an angle greater than 90° away from the upper face of the body portion to fit beneath sheathing or the like and bear against a base to form a tight joint, and a depending flange portion along the opposite edge of said horizontal body portion and inclined at an angle less than 90° toward the lower face of said horizontal body portion thereby to tightly engage a moulding or the like to form a tight joint.

In testimony whereof I affix my signature.

GORDON T. WHITAKER.
